SPINNFABRIK, OF TANNWALD, CZECHOSLOVAKIA, A JOINT-STOCK COMPANY

HIGH-DRAFT SYSTEM FOR SPINNING MACHINES

Application filed August 10, 1928, Serial No. 298,856, and in Austria August 25, 1927.

In high draft systems for spinning machines the pressure on the rove (roving or sliver) when passing between the retarding or gripping rollers ought to be very small in order to prevent deterioration of those fibres (staples) which are longer than the distance between the nipping point of the drawing rollers and that of the gripping rollers, this distance being also made small for the purpose of reducing as far as possible the number of "swimming" fibres. In the known high draft systems both these conditions are met by making the top (pressure) roller of the gripping rollers of small diameter and of very small weight. This light roller is rotated by friction partly on the roving and partly on its co-acting bottom roller and therefore its speed is varying to a considerable extent, as the circumferential speed of said roller is different from the velocity of the rove or sliver. From this fact inconveniences result for the stretching process, all the more, as all the accidental forces, to which the entire machine may be exposed, such as for instance mechanical shocks, are also imparted to the said light roller.

For doing away with these drawbacks it has already been proposed to have the said light top roller driven from its lower roller by means of a gearing, but in practice this way has not proved quite satisfactory.

The cause of the unreliable working of the light top gripping roller is its little inertia corresponding to its small weight. But increasing the resistance due to inertia will only lead to success, if thereby the pressure is not augmented, to which the roving is exposed.

According to the present invention this problem is solved by loading the top roller in question at a point distant from the roving so that the roller will take up a position oblique to its lower or bottom roller and will only run on an edge of the latter, or else—by way of an equivalent arrangement—its one edge will run on the mantle surface of the lower roller. The pressure, exercised by the roller on the roving, will thus depend upon the load of the roller, upon the distance of the point, where the roller is supported from the force acting on the axle of the roller and upon the distance

of the said supporting point from the pressure point (roving). Consequently by suitably choosing or adjusting these distances the possibility is given of reducing even with a greater load the pressure to any desired degree. As thus the pressure roller can be subjected to a high load and its inertia-resistance increased, all the accidental forces will not be able of exercising any substantial influence on it. Moreover the pressure exercised by the edge of the one roller on the cylindrical surface of the other is relatively high, a constant and reliable engagement of the two rollers being ensured thereby. A further improvement of the device consists in positively driving the upper roller by providing it and, if desired, also the lower roller with teeth, flutes, grooves or the like which thus obviously constitute a gearing.

In the annexed drawing five embodiments of the invention are illustrated by way of examples, the Figures 1 and 2 showing the first one by a partly sectional elevation and by a plane view respectively, Figure 3 an elevation of the second, the Figures 4, 5 and 6 partly sectional elevations of further modifications and Figure 7 a plane view of the device shown by Figure 6. In practice symmetrically arranged pairs of such devices are generally employed, but in the drawing the single devices are shown only.

In Figure 1 the top or pressure roller is marked 1, its axle 2 and the lower cylinder 3, the top roller 1 being constituted by a tube-like friction bush provided on its one end with an inwardly projecting collar 4, which serves as bearing or guide for the axle 2. A guide for the journal 5 at the other end of the bush and also for the corresponding end of the axle 2 is constituted by a suitably shaped member 8 provided with the recesses 6 and 7, which recesses allow the ends of the bush and of the axle to perform a slight vertical movement when rotating. The member 8 itself is mounted in a bar 9 forming part of the frame of the entire drawing apparatus and corresponding to the normal bearing bar of the known apparatus. The middle part of the axle 2 imagined to be common to a pair of symmetrically arranged devices is thickened 100

and, if desired, also loaded for instance by a weighted arm 2^a. The top roller 1 will under these conditions take up a position oblique to the lower nipping roller, this obliquity being 5 exaggerated in the drawing.

If P is the component acting on the collar 4 of the force exercised by the load of the axle, the pressure D exercised on the roving L is to be stated from the equation $P.a = D.b$, 10 wherein a is the distance of the force from the supporting edge and b the distance of the centre line of the roving from said edge.

The distance of the collar 4 from the supporting edge ought to be small in order to 15 augment the friction pressure, by which the top roller engages with the lower roller. By providing grooves 10 at the place, where the rollers engage, (Figure 3) their engagement can be made more effective. Instead of the 20 grooves little teeth 10^a (Figure 1) may be provided or any other equivalent means ensuring the engagement of the two rollers.

In the embodiment as shown by Figure 4 the pressure roller 11 is on both its ends provided with journals 12 and 13 respectively, the journal 12 turning in the normal recess of the so-called bearing bar, whilst the journal 13 is guided by a claw 14 carried either by the front roller or by the back roller. The excentrical 30 load is obtained by the roller 11 being partly hollow, so that its centre of gravity lies a distance apart from the middle of the roller. Also in this case there exists the relation $P.a = D.b$, wherein P is the weight of the pressure roller 11.

The same effect as with a hollow roller may be obtained with a full roller (Figure 5) when the latter is composed of two parts 15 and 16 of different specific weight.

40 Also the pressure roller shown in Figures 6 and 7 consists of two parts 17 and 18 and in addition thereto is—similarly to the top roller of Fig. 4—for part of its length hollow. The journal 19 is provided on part 17 having a hollow space and the journal 20 on part 18, which in this case has the form of a bush inserted into the hollow space of part 17. The bush 17 is at the place, where it runs on the edge of the bottom roller provided with flutes, the 45 edges of which flutes form teeth 10^a such as are also seen in Figs. 1 and 2. As the bottom roller is also fluted to its entire length for ensuring a better adhesion or gripping of the sliver, the teeth 10^a of the top roller will engage with the teeth formed by the flutes of the bottom roller, thus constituting means for positively driving the top roller.

What I claim is:

1. In a high draft system for spinning machines of the type having a plurality of pairs of drawing rollers, wherein one roller of one pair of said rollers constitutes a gripping roller and is weighted near one end thereof and mounted on top of the lower roller in such a 60 manner that the roving therebetween causes

the top roller to assume a position oblique to the lower roller so that the weighted end thereof runs on the adjacent end of the lower roller to be driven thereby.

2. In a high draft system for spinning machines of the type having a plurality of pairs of drawing rollers, wherein one roller of one pair thereof constitutes a gripping roller and is weighted near one end thereof and mounted on top of the lower roller in such manner that the roving therebetween causes the top roller to assume a position oblique to the lower roller so that the weighted end thereof runs on the adjacent end of the lower roller and is driven thereby, the said top gripping roller being in the form of a bush provided with a guide near its one end and providing a clearance so, that it is capable of assuming the oblique position.

3. A high draft system for spinning machines of the type having a plurality of pairs of drawing rollers, wherein one roller of one of said pairs constitutes a gripping roller weighted near one end thereof and mounted on top of the lower roller in such manner that the roving therebetween causes the top roller to assume a position oblique to the lower roller so that the weighted end thereof runs on the adjacent end of the lower roller to be driven thereby, the said top gripping roller being in the form of a bush, an axle projecting through the bush and an inwardly projecting collar on one end of the bush and providing a clearance about the axle so that the said bush is capable of assuming the oblique 100 position.

4. In a high draft system for spinning machines of the type having a plurality of pairs of drawing rollers, wherein one roller of one of said pairs constitutes a gripping roller weighted near one end thereof and mounted on top of the lower roller in such manner that the roving therebetween causes the top roller to assume a position oblique to the lower roller and the weighted end thereof running on the adjacent end of the lower roller to be driven thereby, the said top gripping roller being in the form of a bush, guiding means at one end of the bush including an inwardly projecting collar on the bush, and a weighted axle projecting into the bush and spaced from the edges of the collar.

5. In a high draft system for spinning machines of the type having a drawing apparatus embodying a draw bar and a plurality of pairs of drawing rollers, wherein one roller of one of said pairs of rollers constitutes a gripping roller weighted near one end thereof and mounted on top of the lower roller in such manner that the roving therebetween causes the top roller to assume a position oblique to the lower roller so that the weighted end thereof runs on the adjacent end of the lower roller to be driven thereby, an axle for the roller, the said top gripping 120

roller being in the form of a bush and mounted on the axle, and a guiding member for the bush as well as for the axle mounted in the bearing bar of the drawing apparatus.

5 6. In a high draft system for spinning machines of the type having a plurality of pairs of drawing rollers, wherein one roller of one of said pairs of rollers constitutes a gripping roller having its center of gravity situated near one of its ends and mounted on top of the lower roller in such manner that the roving therebetween causes the top roller to assume a position oblique to the lower roller, and the heavier end of the top roller running on the adjacent end of the lower roller to be driven thereby.

10 7. In a high draft system for spinning machines of the type having a plurality of pairs of drawing rollers, wherein one roller of one of said pairs constitutes a gripping roller which at one end is hollow for part of its length and is mounted on top of the lower roller in such manner that the roving therebetween causes the top roller to assume a position oblique to the lower end, and the heavy end of the top roller running on the adjacent end of the lower roller to be driven thereby.

15 8. In a high draft system for spinning machines of the type having a plurality of pairs of drawing rollers, wherein one roller of one of said pairs of rollers constitutes a gripping roller composed of two parts, each of which is provided with a journal and has the form of a bush, the bush of one part being inserted into the bush of the other part, and one of said parts being heavier than the other and said top gripping roller being mounted on top of the lower roller in such manner that the roving therebetween causes the top roller 20 to assume a position oblique to the lower roller and arranged so that the heavier part of the top roller runs on the adjacent end of the lower roller to be driven thereby.

25 9. In a high draft system for spinning machines of the type having a plurality of pairs of drawing rollers, wherein one roller of one of said pairs of rollers constitutes a gripping roller loaded near one end thereof and mounted on top of the lower roller in such manner that the roving therebetween causes the top roller to assume a position oblique to the lower roller and said loaded end thereof running on the adjacent end of the lower roller to be driven thereby.

30 10. In a high draft system for spinning machines of the type having a plurality of pairs of drawing rollers, wherein one roller of one of said pairs of rollers constitutes a gripping roller weighted near one end thereof and mounted on top of the lower roller in such manner that the roving therebetween causes the top roller to assume a position oblique to the lower roller, the said weighted end thereof running on the adjacent end of the lower roller to be driven thereby, and the

35 weighted end of the top roller and the adjacent bottom roller being fluted so that they engage each other in the manner of a gearing.

40 In testimony whereof I have signed my name to this specification.
